UNITED STATES PATENT OFFICE.

MORRIS B. WEINSTEIN, OF STEUBENVILLE, OHIO.

BAG-FASTENER.

1,032,456.

Specification of Letters Patent. Patented July 16, 1912.

Application filed March 16, 1912. Serial No. 684,315.

To all whom it may concern:

Be it known that I, MORRIS B. WEINSTEIN, a citizen of the United States, residing at Steubenville, in the county of Jefferson and 5 State of Ohio, have invented certain new and useful Improvements in Bag-Fasteners, of which the following is a specification, reference being had to the accompanying drawings.

10 This invention comprehends certain new and useful improvements in paper bags and fasteners therefor and the invention has for its primary object a simple and efficient construction of device of this character which 15 may be manufactured at a relatively low cost, not appreciably greater than the ordinary paper bag, and which may be securely sealed without the use of cord, twine, or the like.

20 The invention also has for its object an improved construction of bag fastener of the type embodying pliable sealing tongues that are secured to the top portion of the bag at the mouth thereof and that are adapted to 25 be folded around the side edges of the bag after the mouth portion has been folded upon itself one or more times as desired, the parts being so arranged that there will be very little if any liability to tear the bag.

30 And the invention also aims to generally improve devices of this class and to render them more useful and commercially desirable.

For a full understanding of the invention, 35 reference will be had to the following description and accompanying drawings in which,

Figure 1 is an elevation of a sack or bag equipped with my improved fastening devices. Fig. 2 is a fragmentary sectional view on an enlarged scale, the section being 40 taken on the line 2-2, of Fig. 1. Fig. 3 is a detail perspective view of one of the sealing tongues detached, and, Fig. 4 is a fragmentary perspective view of the mouth portion of the bag in closed or sealed condition.

45 Corresponding and like parts are referred to in the following description and indicated in the accompanying drawings by like reference characters.

50 Referring to the drawing, the numeral 1 designates a bag which is preferably formed of paper, although it is to be understood that the invention is not limited in this regard, and 2 designates sealing tongues which 55 are secured to the exterior wall of the bag

or sack near the mouth rim thereof as clearly illustrated in the drawings. Each of the locking tongues is composed of a relatively narrow strip of metal or other pliable substance or material and is formed near one end with punched out tangs 3 that are clenched through the wall of the bag and bent down on the inner side thereof, said tangs penetrating reinforcing strips 4 that 60 are disposed on the inner side of the bag and that are preferably formed of light pasteboard or other similar material of somewhat heavier stock than the material out of which the bag itself is formed. By means of these 65 reinforcing strips tendency of the tongues 2 to tear out is reduced to a minimum.

From as much of the description as has preceded in connection with the accompanying drawings, it will be understood that in 70 the use of a bag or sack constructed in accordance with my invention, after the contents have been poured into the sack, the mouth rim thereof is folded upon itself 75 along transverse lines, as shown, any desired 80 number of times, and the relatively free ends of the sealing tongues 2 are then bent down around the side of the sack and crimped or pinched so as to securely hold the mouth in sealed condition. Preferably 85 each of the tongues is formed at both ends with relatively short spurs 5, designed to penetrate the material of the bag so as to assist in holding the mouth sealed and to also further reduce the liability of the 90 tongues tearing away.

It will thus be seen that I have provided a very simple bag or sack and fastening devices therefor which may be cheaply manufactured and the parts readily assembled 95 and by the use of which the bag may be securely sealed without the use of cord or twine.

It is to be particularly noted, as indicated in Fig. 1 and clearly shown in Fig. 2, that 100 my improved fastener is applied to a bag or sack of the bellows type, and that the sealing tongues 2 are secured to the face of one of the intermediate plies of bellows folds. Consequently, the sealing tongues will be 105 protected when the bags or sacks are in their flat condition and are handled as such, so as to avoid any liability of becoming accidentally detached, the tongues interfering in no wise with the operation of opening the sack 110 to its fullest extent, as is manifest. It is also to be noted that by having the sealing

tongues 2 separate and distinct from each other and laterally spaced from each other, as clearly illustrated in Fig. 1, the bag or sack may be folded along a longitudinal line, if desired, which would not be possible or practical if the two tongues were composed of a single strip of metal extending entirely across the bag or front face of the sack. Furthermore, by having the two sealing tongues separate and distinct from each other, they may be secured in between the bellows folds which, of course, is not possible with a construction where the sealing tongues are composed of a single or integral strip extending entirely across the bag.

What I claim is:—

As a new article of manufacture, the herein described bag of the bellows type provided near its mouth with separate and distinct sealing tongues, said tongues being secured to the inner bellows folds of the sack at the side and of a length to project outwardly beyond said folds. ²⁰

In testimony whereof I hereunto affix my signature in the presence of two witnesses. ²⁵

MORRIS B. WEINSTEIN.
